WAYNE RAWLEY AND ORAND A. PLUSKEY, OF PITTSBURGH, PENNSYLVANIA, ASSIGNEES TO BLOW KNOX COMPANY, OF PITTSBURGH, PENNSYLVANIA, A CORPORATION OF NEW JERSEY.

APPARATUS FOR REMOVING SURPLUS SPELTER FROM GALVANIZED ARTICLES.

Application filed November 13, 1924. Serial No. 749,649.

The present invention relates to coating, and more particularly to the removal of surplus spelter from galvanized articles, such as angles or other structural shapes.

5 It is of great importance in galvanizing that the coating of zinc which is applied to the surfaces of the article shall be of uniform thickness throughout, because if it is thicker at certain places than at others it is much more likely to be peeled off at those places by shrinkage or contact with other materials during handling, thereby leaving exposed parts of the steel for corrosion. Therefore, the perfectness of the coating of 15 zinc and the uniformity of the thickness of such coating is of greater importance than the thickness of the coating itself. Our present invention resides in a method and an apparatus for removing surplus spelter from galvanized articles involving the use of streams of air or other suitable fluid for that purpose. We have found that by suitably applying streams of air to the surfaces of a galvanized article, the coating thereof 20 is rendered uniform and its thickness can be regulated with great accuracy. There is thus not only an improvement in the protection against corrosion, which is the object of galvanizing, but there is also a saving in 25 the amount of spelter required and a consequent saving in the cost of galvanizing.

In the accompanying drawings we have 30 illustrated our invention as applied to the removal of surplus spelter from angles, but it will be apparent that by suitable modifications the same character of apparatus may be utilized for removing the surplus spelter from channels, I-beams or any other structural shapes.

40 In the drawings:

Figure 1 is an end elevation of a galvanizing apparatus, partly broken away, embodying the present invention;

Figure 2 is a view on a larger scale of the 45 portion of the apparatus shown in Figure 1 embodying our invention;

Figure 3 is a detail view showing a side elevation of the apparatus disclosed in Fig. 2;

Figure 4 is a transverse horizontal section in the plane of line IV—IV of Fig. 3;

Figure 5 is a similar view in the plane of line V—V of Fig. 3;

Figure 6 is a detail view on a large scale illustrating one end of a portion of the rest

on which the parts which have been galvanized are supported after they are lifted out of the bath;

Figure 7 is a detail view illustrating one of the nozzles located over a bar which has been galvanized, illustrating how the shape 60 of the nozzle conforms to the shape of the galvanized piece;

Figure 8 is a bottom plan view of the arrangement shown in Fig. 7;

Figure 9 is a detail plan view of one of 65 the nozzles for blowing against the under surface of a piece which has been galvanized;

Figure 10 is a detail view showing a side elevation of the nozzle disclosed in Fig. 9 with a piece which has been galvanized supported thereabove and disclosing how the 70 lower nozzles conform to the shape of the piece which has been dipped; and

Figure 11 is a view similar to Fig. 8, showing a nozzle provided with a single elongated orifice in place of a plurality of small 75 holes.

We have illustrated our invention herein in connection with galvanizing apparatus of the character shown and described in our 80 co-pending application Serial No. 544,507, filed March 17, 1922.

Referring particularly to Figure 1, this apparatus comprises a charging platform 2 having supports 3 thereon for receiving the 85 shapes 4 to be galvanized. The shape, in the present instance angles, may be supplied to the supports 3 in any desired manner but are preferably arranged thereon substantially as illustrated whereby they may be easily inspected by an operator or operators on the charging platform. From this platform the shapes may be delivered in groups of any desired number to a galvanizing pot 5 by means of suitably arranged charging conveyors 6. 90 The shapes as discharged into the galvanizing pot may be moved from one side thereof to the other by suitable pushers 7 and after the desired interval may be elevated from the spelter bath by a suitable elevating 100 mechanism comprising a crank 8 adapted to be operated by a handwheel 9.

Mounted upon the galvanizing pot adjacent one end thereof is a guide frame 10. At one side of this frame is the hood 11 which 105 extends over the lower end of the conveyors 6. Bolted to the base of the guide frame is a support 12 for the work. This support has

a serrated upper edge providing a number of projections 13 adapted to extend into the angles between the sides of the shapes 4, as illustrated more particularly in Figure 6. 5 Intervening between the projections 13 are other and smaller projections 14. It will be seen that the serrated upper edge of the support 12 is so formed that the shapes 4 are only engaged by the support at the lower edges 10 of the sides of the shapes. After the shapes have been elevated by means of the crank 8 and placed on the support, they may be drawn along the support by means of suitable hooks 15 (Figure 3) each connected at one end to 15 a conveyor (not shown) and having its other end inserted in an opening in the end of the corresponding shape.

Mounted on top of the guide frame is a vertically extending fluid cylinder 16 having 20 a piston 17 working therein. The cylinder is open to the atmosphere at its upper end and the piston has a piston rod 18 extending through a stuffing box 19 at the lower end of the cylinder. The piston has its lower end reduced and screw threaded and this screw threaded end extends through the horizontal flange of an angle 20, the angle being secured to the piston by a nut 21. The angle 20 extends horizontally between the sides of 25 the guide frame and has bracket members 22 bolted to the ends thereof. These bracket members are slotted to receive vertical guide ribs 23 on the sides of the guide frame 10, whereby vertical movements of the angle 20 30 are guided.

The angle 20 constitutes a support for the upper blowing nozzles 24. These nozzles conform to the shape of the articles being galvanized and are connected to a pipe 25. The 40 pipe 25 and nozzles 24 are secured to bars 26 adjustably and detachably mounted on the horizontal flange of the angle 20 by bolts 27 passing through slots 28 in the bars. This adjustable mounting of the bars 26 permits 45 the upper nozzles to be adjusted horizontally and also permits of a rapid change to a different size or shape of nozzles. The pipe 25 and nozzles 24 are secured to vertical legs 29 of the bars 26 by U bolts 30. These U bolts also 50 extend through a stop bar 31 which is slotted to permit a slight vertical adjustment thereof. By reference to Figure 2, it will be seen that the lower edge of the stop bar projects slightly below the apexes of the angles between the 55 sides of the nozzles 24. When the piston 17 is permitted to descend in the cylinder 16, the upper nozzles are prevented from descending into contact with the shapes by the stop bar 31 whose lower edge engages the corners of the 60 shapes.

Associated with the support 12 is a set of lower nozzles 32 which conform to the shape of the articles to be galvanized and are integral with a pipe 33. These lower nozzles are 65 adjustably clamped to the support 12 by

bolts 34 and clamp plates 35. There are thus provided two sets of opposing nozzles, 24 and 32, one set below and one set above the shapes on the support 12, the upper nozzles being mounted so that they can be raised to allow 70 placing the shapes on the support and lowered when the air is to be blown against the shapes.

Referring to Figures 7 to 10, inclusive, which are respectively an elevation of one of 75 the upper nozzles, a bottom plan view thereof, a top plan view of one of the lower nozzles and a side elevation of the latter nozzle, the nozzles are preferably provided with a series of small holes 36, for the reason that small 80 holes through which jets of air are blown are not likely to become plugged up or otherwise obstructed or to become distorted in use. These holes are preferably drilled so as to direct the streams of air against the surfaces of 85 the shapes at substantially right angles to the longitudinal axes thereof. In Figures 9 and 10, we have shown the lower nozzle provided with a short slot 37 at its apex in order to permit a relatively larger amount of air to be 90 blown against the lower surface of the shape at the apex of the angle between its sides. While it is preferred to employ the series of small holes in the nozzles, a single slot 38, as shown in Figure 11, may be employed. 95

The lower nozzles may be connected by permanent piping 39 to the supply line 40, while the upper nozzles are connected to the supply line through a flexible hose 41. It is desirable to provide a pressure regulator 42 in the pipe 100 line 43 leading to the air cylinder 16 so as to render the latter independent of fluctuations in the pressure line which is used for blowing. It is also desirable to provide a pressure regulator 44 in the blowing line so that the pressure 105 may be adjusted therein to that most suitable for cleaning the work and regulating the thickness of the galvanizing coating. By providing two such pressure regulators, the proper air pressures are obtained in both the 110 blowing line and the line leading to the air cylinder. A four-way valve 45, operated by a lever 46, is provided between the supply line 40 and the blowing line and the line leading to the air cylinder. Throwing the lever in one direction first stops the blowing process and lifts the upper nozzles from the work, while throwing the lever in the opposite direction allows the upper nozzles to descend and then turns on the air for 115 blowing. An angle valve 47 may also be provided in the line 43 leading to the air cylinder so that that line may be operated independently whenever that is desirable. 120

It will be obvious that the jets of air blown 125 against the surfaces of the shapes as they are withdrawn from the galvanizing pot on the support 12 will operate not only to clean the shapes and to blow off surplus spelter, but also that they will have some cooling effect 130

and it is therefore possible, by regulating the speed with which the work is withdrawn from the spelter bath and the pressure of the air, not only to obtain the right thickness of spelter but also to chill the surface of the work sufficiently to cause the spelter to congeal against it almost immediately after passing the nozzles. While it is believed preferable to employ air for removing the surplus spelter, the invention is not limited to the use of this fluid, as any other suitable fluid other than air may be employed.

The advantages of the present invention will be at once apparent from the foregoing. By employing streams of air directed against the surfaces of the galvanized articles, the thickness of the galvanizing coating can be nicely regulated and all impurities can be removed from the outside surfaces of the articles. Furthermore, it is possible by this method to secure a more uniform coating than is the case when the surplus metal coating is removed by scraping or when the articles are allowed to drip. Therefore, a thinner coating may be utilized, thereby effecting a saving in the amount of spelter employed.

While we have shown and described a preferred embodiment of means for carrying out our improved process, the invention is not limited to the exact details shown, but may be otherwise embodied within the scope of the appended claims without departing from the spirit of the invention.

We claim:

1. Means for removing surplus spelter from galvanized shapes, comprising a supporting rest over which a plurality of coated shapes are adapted to be withdrawn from the spelter bath, means for withdrawing the shapes and groups of nozzles associated with the supporting rest for blowing streams of

air against the upper and lower surfaces of the individual shapes as they are withdrawn.

2. Means for removing surplus spelter from galvanized shapes, comprising a support over which a plurality of coated shapes are adapted to be withdrawn from the spelter bath, nozzles for blowing streams of air against the upper and lower surfaces of the shapes as they are withdrawn, and means for raising and lowering the nozzles for blowing the air against the upper surfaces of the shapes in order to permit the shapes to be placed on said support.

3. Means for removing surplus spelter from galvanized shapes, comprising a support over which a plurality of coated shapes are adapted to be withdrawn from the spelter bath, said support being shaped so as to make substantial line contact only with said shapes, a set of nozzles associated with said support for blowing a fluid against the lower surfaces of said shapes as they are withdrawn, a set of nozzles for blowing a fluid against the upper surfaces of said shapes, a fluid pressure cylinder, a piston for raising and lowering the upper set of nozzles, piping connecting said sets of nozzles and the fluid cylinder with a source of pressure fluid supply, and a single valve for controlling the supply of fluid to the nozzles and cylinder.

4. Means for removing surplus spelter from galvanized articles, including a supporting rest, a nozzle supporting bracket, a plurality of nozzles on the bracket over the supporting rest, and means for moving the bracket toward and away from the supporting rest.

In testimony whereof we have hereunto set our hands.

WAYNE RAWLEY.
